UNITED STATES PATENT OFFICE.

JAMES P. GARDNER, OF CHICAGO, ILLINOIS, ASSIGNOR TO THE REDUCING MACHINE COMPANY, OF CHICAGO, ILLINOIS.

MASSAGE-MACHINE.

1,265,074.

Specification of Letters Patent.

Patented May 7, 1918.

Application filed October 12, 1914. Serial No. 866,316.

To all whom it may concern:

Be it known that I, JAMES P. GARDNER, a citizen of the United States, and resident of Chicago, in the county of Cook and State 5 of Illinois, have invented certain new and useful Improvements in Massage-Machines, of which the following is a specification.

This invention relates more particularly to a machine for giving massage treatment 10 wherein substantially solid or non-yielding contact rollers or the like are used, and may be given any desired amount of pressure against the body.

Among the objects of this invention are to 15 provide a simple and efficient machine of this character which is readily adjustable in various ways in order to conveniently reach different portions of the body, and to provide such other advantages as will appear from the following description.

In the accompanying drawings illustrating this invention:

Figure 1 is a front view of the machine;

Fig. 2 is a side view partially in section, 25 as indicated by the line 2—2 of Fig. 1;

Fig. 3 is a plan view of the base portion; and

Fig. 4 is a sectional detail taken on the line 4—4 of Fig. 2.

30 In general, my improved machine may be said to consist in a plurality of massage devices arranged to operate in vertical planes, and oppositely disposed so as to be able to engage with the opposite sides of the 35 body, with means for adjusting said devices to bring them in contact with different portions of the body.

In the particular form shown in the drawings, 5 indicates a base having a guideway 6 therein for a slidable support or platform 7. This platform is provided with a downwardly depending lug 8, which is engaged by a screw 9 for adjusting the same longitudinally. The platform 7 is made in the form shown 45 particularly in Fig. 3, and serves as a platform for the person to be acted upon, as well as a support for a portion of the massage devices. Two stands 10 are secured at one end of the base 5, and serve as bearings 50 for a swinging arm or frame 11, this frame having suitable trunnions engaging therewith. A shaft 12 has its bearings in the trunnions of the frame 11, and is provided with two sprocket wheels 13. The 55 upper ends of the side portions of the frame

11 are provided with guideways for slideable bearings 14, for a shaft 15, which shaft is provided with sprocket wheels 16 arranged in alinement with the sprocket wheels 13. Springs 17 are interposed between the bearings 14 and followers 18, and screws 19 are provided for adjusting the followers 18 to adjust the pressure on the bearings. Two chains 20 pass around the respective pairs of sprocket wheels 13 and 16, and serve to 60 carry horizontal brackets 21 for the rollers or contact members 22, which are preferably rotatably mounted in said brackets. These rollers may be made in any desired form and of any suitable material, but I 70 prefer to make them of wood, and from one and one-half to two inches in diameter.

Two stands 23, similar to the stands 10, are mounted on the adjustable support 7, and serve as bearings for a swinging frame 75 or arm 24. A shaft 25 passes through the trunnions of the arm 24, and carries sprocket wheels 26. A second shaft 27 is yieldingly mounted in the upper end of the frame 24 in the manner just described in connection 80 with the shaft 15, and carries sprocket wheels 28. Chains 29 pass around the sprocket wheels 26 and 28, and are provided with brackets 30 carrying rollers 31.

The upper ends of the swinging frames 85 11 and 24 are intended to be moved toward or away from each other for adjusting them to the body of the person to be treated, and also for regulating the pressure. This may be done by means of various expedients, but 90 as shown I have provided a stand 32 at the rear of the base 5, with pivoted bearings 33 and 34 for the adjusting screws 35 and 36. These screws pass respectively through nuts 37 and 38, which are pivoted to the rear 95 arms of the frames 11 and 24, and are provided at their outer ends with cranks 39 and 40. By turning one or the other of these cranks, the corresponding frame is 100 swung inwardly or outwardly as desired.

The shafts 12 and 25 serve as driving 105 shafts for the chains or belts, and these shafts may be driven continuously in either direction as desired, or may be given an oscillating or reverse movement in order to give a reciprocating movement to the portions of the chains engaging with the body of the person. A simple form of driving mechanism comprises worm wheels 41 and 42, which are secured to the shafts 12 and 110

25, and are engaged by worms 43 and 44 on a drive shaft 45. The shaft 45 is driven by a motor 46, which may be of the reversible type in order to give a reverse movement to 5 the massage devices. It will be readily seen that by giving a reverse movement to the belts or chains, the rollers or massage devices will be reciprocated so as to move to and fro longitudinally of the body. The 10 ends of the worm 44 are supported in a bracket 47, which is secured to one of the stands 23, and this worm engages with a feather 48 in the shaft 45, so that the worm may move along the shaft, and will remain 15 in driving engagement with the worm wheel as the platform 7 is adjusted. The driving gearing is preferably inclosed in an oil box 49 in the manner indicated.

While this improved machine is adapted 20 for various therapeutic treatments, it is especially adapted for the reduction of fat. Fat occurs in different persons on different portions of the body, and, in order to reach the various portions, a machine of this character 25 must be capable of considerable adjustment. For instance, if the fat occurs on the lower portions of the limbs, the person to be treated may stand in the machine in the position indicated in Fig. 1, and the adjustable platform 7 is moved inwardly until 30 the rollers engage closely with the calves of the legs or other portions of the lower limbs which are desired to be acted upon. The motor will drive the shafts 12 and 25 in 35 the desired direction, preferably so that the inner flights of the chains will move upwardly, as the upward movement of the rollers is in most cases considered preferable. If the treatment is to be given more 40 particularly around the hips or abdomen, the platform 7 may be moved outwardly, and the swinging frames 11 and 24 adjusted inwardly at the top, until the rollers engage 45 with the portion of the body desired. Instead of standing in the position indicated in Fig. 1, the person to be acted upon may stand sidewise in the machine, in which case 50 the rollers may be brought to engage with the front or back portions of the body instead of the sides. In fact, the machine is so adjustable that it may be used in a large variety of ways, which will readily suggest themselves to those familiar with this art.

The sprocket wheels for the chains are 55 made sufficiently large so that the inner flights of the chains may be pressed considerably out of alinement in order to allow a large number of the rollers on each chain to come in contact with the curved portions of 60 the body; or, in other words, to allow the device to conform to the contour of the body, and the yielding adjustable bearings for the outer sprockets provide means whereby the tension on the chains may be 65 regulated. The pressure of the rollers

against the body may then be regulated by adjusting the springs 17, and by the adjusting screws 35 and 36.

Having thus described my invention, which, however, I do not wish to limit to the exact form or arrangement shown, except as specified in the following claims, what I claim and desire to secure by Letters Patent is:

1. In a massage machine, the combination 75 of oppositely disposed vertically arranged yielding carriers, horizontal rollers mounted on said carriers, means for adjusting said carriers to bring the rollers in contact with the body of a person, and means for moving 80 said carriers vertically to cause the rollers to move along the body.

2. In a machine of the character set forth, the combination of oppositely disposed belts, horizontal rollers carried by said belts, 85 adjustable yielding supports for said belts, means for driving said belts in substantially vertical directions, and means whereby the belts may be moved toward or away 90 from each other.

3. In a massage machine, the combination of a base, bearings on said base, means for adjusting said bearings toward or away from each other, frames mounted to swing in said bearings, means for adjusting the 95 upper ends of said frames toward or away from each other, shafts in the upper and lower ends of said frames, sprocket wheels carried by said shafts, chains passing around the sprocket wheels of the respective frames, 100 means for driving said chains, and horizontal rollers mounted on said chains and adapted to engage with the body of a person.

4. In a massage machine, the combination 105 of a base, stands mounted on said base, two frames mounted to swing in said stands, driving shafts at the lower ends of said frames, shafts mounted in the upper ends of said frames, sprocket wheels on the driving shafts and last-named shafts, chains passing around the sprocket wheels of the respective frames, means for turning said driving shafts, supports on said chains, and rollers mounted in said supports and adapted to 110 engage with the body of a person.

5. In a massage machine, the combination 115 of an arm or frame pivoted at its lower end and adapted to swing in a vertical plane, a driving shaft at the lower end of said frame, a second shaft yieldingly mounted in the upper end of said frame, wheels on said shafts, belts passing around said wheels, brackets carried by said belts, horizontally arranged rollers mounted in said brackets, means for turning said driving shaft, and 120 means for adjusting the upper end of said frame.

6. In a machine of the character set forth, the combination of a base, bearings at one 125 end of said base, a frame pivoted to said

- bearings, a driving shaft at the lower end of the frame, wheels on said driving shaft, a second shaft yieldingly mounted in the upper end of said frame, means for adjusting the tension on said last-named shaft, wheels on said last-named shaft, belts passing over the wheels of the driving shaft and said last-named shaft, horizontally arranged brackets carried by said belts, rollers mounted in said brackets, a slideable platform mounted on said base, means for adjusting said platform, bearings on said platform, a frame pivoted to said last-named bearings, a drive shaft at the lower end of said last-named frame, a shaft yieldingly mounted in the upper end of said last-named frame, means for adjusting the tension on said last-named shaft, wheels on said driving shaft and said last-named shaft, belts passing around said wheels, horizontally arranged brackets carried by said belts, rollers in said brackets, means for turning said driving shafts, an upright connected with said base, and adjusting screws between the upright and said frames for supporting and adjusting the upper ends of said frames. 7. In a machine of the character set forth, the combination of a base, bearings at one end of said base, vertically arranged massage devices carried by said bearings, a platform slidably mounted on said base, bearings on said platform, vertically arranged massage devices carried by said bearings, and means for adjusting said platform longitudinally of the base. 8. In a massage machine, the combination of a base, two oppositely disposed massage devices pivotally mounted on said base, an upright on said base, and screws connecting said upright and the massage devices for swinging said devices and holding them in adjusted position. 9. In a massage machine, the combination of two oppositely disposed vertically arranged frames, vertically movable massage devices carried by said frames, parallel driving shafts for driving said massage devices, stationary bearings for one of said shafts, adjustable bearings for the other shaft, worm wheels on said shafts, worms engaging with said wheels, a driving shaft on which said worms are mounted, a feather on said shaft for one of said worms, and a bracket connecting between one of the movable bearings and said worm for moving it along the feather. 10. In a massage machine, the combination of a plurality of horizontally arranged rollers adapted to engage with opposite sides of the body, means for yieldingly supporting said rollers, and means for reciprocating said rollers longitudinally of the body when the latter is erect. 11. In a massage machine, the combination of one or more horizontally arranged
- rollers adapted to engage with one side of the body, one or more rollers adapted to engage with the opposite side of the body, means for adjusting the pressure of the rollers against the body, and means for reciprocating said rollers vertically. 12. In a machine of the character set forth, the combination of a plurality of horizontally arranged rotatable massage devices for engagement with opposite sides of a person, means for yieldingly supporting said devices, and means for adjusting the pressure of the devices against the body. 13. In a machine of the character set forth, the combination of a plurality of horizontally arranged non-yielding massage devices adapted to engage with one side of the body, a plurality of similar devices for engagement with the opposite side of the body, means for yieldingly supporting said devices, and power operated means for reciprocating said devices. 14. In a massage machine, the combination of a plurality of horizontally arranged interconnected non-yielding massage devices, means for yieldingly supporting said devices, means for adjusting the pressure of the devices against the body of a person, and power operated means for reciprocating said devices. 15. A massage machine comprising a plurality of rotatable massage devices adapted to be disposed at opposite sides of the body, means for supporting said devices and pressing them against the body, and power operated means for moving said devices lengthwise of the body. 16. In a massage machine, the combination of a plurality of horizontally arranged rollers adapted to yieldingly engage with opposite sides of the body of a person, and means for reciprocating said rollers vertically. 17. In a massaging machine, the combination of a pair of supports, reciprocatory members mounted on said supports, a series of rollers carried by each of said members, and spring means in the connection between said members and said supports, substantially as described. 18. In a massaging device, the combination of a rigid frame, a sidewise movable frame, a series of rollers carried by each frame, means for causing bodily movement of said rollers relative to said frame, and spring means in the connection between each series of rollers and their support, substantially as described. 19. In a massaging device, the combination of a fixed standard, and a sidewise movable standard, a series of rollers reciprocably mounted on each standard, means for reciprocating said rollers, and means for adjusting said sidewise movable standard, substantially as described.

20. In a mechanical massaging device, the combination of a base, standards projecting from said base, one set of said standards being movable relative to the other; a roller support adjustably mounted on each of said standards, rollers carried by said roller supports, and mechanical means for reciprocating said rollers and supports, substantially as described.
- 10 21. In a device of the class described, the combination of two standards, a series of rollers mounted upon and adapted for bodily movement, relative to each of said standards, mechanical means for actuating said
- 5 series of rollers, and means for varying the distance between each series of rollers, substantially as described.
22. In a mechanical massaging device, the combination of adjacent standards, means for moving one of said standards relative to the other thereof, a series of rollers reciprocally mounted on each of said standards, and mechanical means for reciprocating said rollers, substantially as described.

JAMES P. GARDNER.
